UNITED STATES PATENT OFFICE.

GEORGE BRADFORD, OF MOUNT VERNON, NEW YORK.

DESIGN FOR A PEN.

Specification forming part of Design No. **11,388**, dated September 2, 1879; application filed July 10, 1879.
[Term of patent 14 years.]

To all whom it may concern:

Be it known that I, GEORGE BRADFORD, of Mount Vernon, in the county of Westchester and State of New York, have invented a new and Improved Design for Pens, of which the following is a specification.

The nature of my design is fully represented in the accompanying drawings, to which reference is made, and in which—

Figure 1 is a face view of a pen illustrating my design. Fig. 2 is a section taken through the broken line *x x*, Fig. 1. Fig. 3 is a cross-section taken through the line *y y*, Fig. 1.

Similar letters of reference indicate corresponding parts.

The object of this invention is to furnish an improved design for pens, the use of which will make the pens neat and ornamental in appearance.

A represents the shank; B, the neck; C, the bowl, and D the point of the pen. In the edges

of the pen, at a little distance from the point, are formed notches E, giving to the said point a shape similar to an arrow-head.

The edges of the bowl C have flanges F formed upon them, which, at the shoulders of the said bowl, are inclined outward, as shown in Fig. 2, and along the sides of the bowl C project at right angles, as shown in Fig. 3.

The flanges F extend down to the notches E. Around the base of the bowl C is formed a curved bead or shoulder, G.

Having thus fully described my invention, I claim as new and desire to secure by Letters Patent—

A design for pens, consisting of the bowl C, with edge-flanges F and curved bead G, arranged as shown and described.

GEORGE BRADFORD.
